UNITED STATES PATENT OFFICE.

ROBERT E. FIVEY, OF CHICAGO, ILLINOIS.

FLUSH-VALVE.

1,202,499.

Specification of Letters Patent.

Patented Oct. 24, 1916.

Application filed January 28, 1916. Serial No. 74,938.

To all whom it may concern:

Be it known that I, ROBERT E. FIVEY, a citizen of the United States of America, and a resident of Chicago, in the county of Cook, State of Illinois, have invented certain new and useful Improvements in Flush-Valves, of which the following is a specification.

This invention relates to that type of flushing valves for water closet and like uses, in which the slow closing of the valve is attained by the slow inflow of pressure fluid into a fluid motor associated with the movable member of the valve, an example 15 of which is shown in my former Patent No. 1,132,570, dated March 23, 1915. And the present improvement has for its object to provide a compact, efficient and economical structural formation and association of 20 parts by which an accurate and convenient regulation of the flow of fluid through the valve at each operation thereof, is attained, all as will hereinafter more fully appear.

In the accompanying drawings:—Figure 25 1, is a central vertical section of a flushing valve embodying the present invention. Fig. 2, is a horizontal section on line α — α , Fig. 1.

Similar reference numerals indicate like 30 parts in both views.

Referring to the drawings, 1 designates the open top casing or housing of the valve, having the usual inlet and outlet chambers 2 and 3 and inlet and outlet necks 4 and 5 35 at its lower end, which latter are preferably arranged in the right angle relation, and with the outlet neck 5 in vertical alinement with the valve mechanism and accessories of the structure.

40 6 designates a lower partition of an approximately V-shape arranged within the casing 1 and separating the inlet chamber 2 from the outlet chamber 3 thereof, with said outlet chamber in communication with the 45 space above the uppermost portion of the partition 6 as shown.

7 designates a central orifice formed in the uppermost portion of the partition 6 and provided with an upturned marginal rim 8 50 forming a seat for the main valve of the structure. Said orifice in an open condition of said main valve, forms a communication between the inlet and outlet chambers 2 and 3, to permit a free passage of fluid from one 55 chamber to the other.

9 designates an intermediate transverse

partition arranged in the interior of the casing 1 in spaced relation to the partition 6 aforesaid, with the intervening space forming a piston chamber 10 for the piston of 60 the main valve hereinafter described.

11 designates a closure cap screwing into a screw threaded portion of the upper bore of the casing 1 and having spaced relation to the intermediate partition 9, with the intervening space forming a containing chamber 12 for the operating mechanism of the valve hereinafter described. In the construction shown the containing chamber 12 is of a larger diameter than the piston 70 chamber 10 aforesaid, so that the intermediate partition 9 may be introduced through said containing chamber and screwed into place in the upper end of the piston chamber, which is screw-threaded for this purpose, and provides a structure capable of 75 ready and convenient assemblage.

13, designates a non-circular head formed on the top of the partition 9 for the convenient turning of the same by the operator. 80

14 designates a central orifice formed in the head 13 and partition 9, and constituting a communicating passage between the piston and containing chambers 10, 12, in an open condition of the auxiliary valve head 85 which controls said orifice 14.

15 designates an annular valve seat carried on the under side of the partition 9 in concentric relation to the orifice 14.

16 designates a vertical passage formed 90 in the wall of the casing 1, and connecting the containing chamber 12 with the outlet chamber 3 together as shown.

17 designates a non-circular head formed on the top of the closure cap 11 for the 95 convenient turning of the same by the operator.

18 designates a central guide bore formed in the cap 11 and adapted to provide a guiding means for the upper end of the 100 valve stem hereinafter described.

19 designates a tubular valve stem arranged vertically in the main casing and in axial relation to the piston chamber 10, and orifices 7 and 14 aforesaid, with its upper end adapted for guiding engagement with the guide bore 18 of the closure cap above described.

20 designates a piston moving in the piston chamber 10, with its lower end carrying 110 a valve head 21 adapted for engagement with the valve seat 8 in the lower and nor-

- mal position of the piston. The piston 20 is of any usual hydraulic type, preferably the cupped ring form shown, and in the present improvement is formed with a central cylindrical bore in which the lower end of the tubular valve stem 19 is adapted independent movement in the opening and closing operations of the mechanism.
- 22 designates a fixed collar surrounding the upper portion of the valve stem 19 with its under surface forming an abutment for a spring 23, which encircles the valve stem, and tends to yieldingly force said valve stem in an upward direction.
- 15 24 designates a rock-arm, preferably of the forked form shown, arranged in the containing chamber 12 aforesaid, with its free end having bearing against the upper surface of the fixed collar 22, and adapted to impart a downward movement to the valve stem 19, aforesaid.
- 25 25 designates a rock-shaft extending transversely through the upper end of the casing 1 and carrying the rock arm 24 aforesaid and providing a means for actuating the same. And to such end the rock shaft 25 will be connected with a moving part of the water closet or like mechanism, to receive automatic operation therefrom.
- 30 26 designates the auxiliary valve head or member heretofore referred to and which is fixedly secured to the valve stem 19, aforesaid, in operative relation to the valve seat 15, and in its normal position adapted to close the orifice or passage 14.
- 27 designates one or more lateral passages formed in the wall of the tubular valve stem 19, and connecting the bore 28 of said valve stem with the piston chamber 10 at a point immediately beneath the valve head 26, above described.
- 29 designates an adjustable valve rod or member, preferably of the needle type shown, movable in the upper portion of the bore 28 of the tubular valve stem 19, with its lower tapering end in operative relation to the lateral passages 27, aforesaid, and adapted to regulate the size of said passages as usual in the present type of valves. To such end the valve rod 29 is formed with a screw-threaded head or enlargement 30 at its upper end and which is in adjustable engagement with a correspondingly enlarged screw-threaded upper portion of the bore of the tubular valve stem 19, as shown in Fig. 1.
- 31 designates a transverse slit or other usual operating means at the upper end of the valve rod 29 aforesaid.
- 35 The operation of the present mechanism is as follows: With a depression of the tubular valve stem 19 by the rock arm 24 and rock shaft 25, the auxiliary valve 26 is moved away from its seat 15, and the passage 14 is opened for communication between the piston chamber 10 and the containing chamber 12, to permit an outflow of fluid from said piston chamber, due to the pressure exerted by the fluid in the inlet chamber 2 against the underside of the piston 20, the effect being to cause a rapid and full opening movement of the main valve 21 carried by said piston. With the closing of the auxiliary valve 26 by the spring 23, fluid under pressure from the inlet chamber 2, passes in a slow manner through the restricted passage 27 into the piston chamber 10, and above the piston 20, to gradually force said piston in a downward direction, and with it the main valve 21 to a closed position, ready for a succeeding operation similar to that above described.
- Having thus fully described my said invention, what I claim as new and desire to secure by Letters Patent, is:—
1. The combination in a flush valve, of an open top casing formed with an upper containing chamber and intermediate piston chamber and lower inlet and outlet chambers, a transverse partition of an approximately V-shape separating said inlet and outlet chambers and having a communicating passage and valve seat, a cap closing the open upper end of the casing and having a central guide bore, a piston in the aforesaid piston chamber formed with a central guide bore, a valve head carried by said piston and controlling the passage between the inlet and outlet chambers aforesaid, a tubular valve stem having vertical movement in the guide bores of the piston and cap aforesaid, and provided with a lateral passage in its wall and opening into the aforesaid piston chamber, means within the valve stem for regulating the size of said lateral passage, an auxiliary valve head carried on said valve stem at a point above the lateral passage aforesaid, a removable partition separating the aforesaid containing and piston chambers and having a central valve seat and passage controlled by said auxiliary valve head, means providing communication between the containing and outlet chambers aforesaid, resilient means for moving the aforesaid valve stem upwardly, and means for imparting positive downward movement to said valve stem, substantially as set forth.
2. The combination in a flush valve, of an open top casing formed with an upper containing chamber and intermediate piston chamber and lower inlet and outlet chambers, a transverse partition of an approximately V-shape separating said inlet and outlet chambers and having a communicating passage and valve seat, a cap closing the open upper end of the casing and having a central guide bore, a piston in the aforesaid piston chamber formed with a central guide bore, a valve head carried by said pis-

ton and controlling the passage between the inlet and outlet chambers aforesaid, a tubular valve stem having vertical movement in the guide bores of the piston and cap aforesaid, and provided with a lateral passage in its wall and opening into the aforesaid piston chamber, means within the valve stem for regulating the size of said lateral passage, an auxiliary valve head carried on said valve stem at a point above the lateral passage aforesaid, a removable partition separating the aforesaid containing and piston chambers and having a central valve seat and passage controlled by said auxiliary valve head, means providing communication between the containing and outlet chambers aforesaid, resilient means for moving the aforesaid valve stem upwardly, and means for imparting positive downward movement to said valve stem, the same comprising a rock shaft extending transversely through the casing, and a rock arm carried on said rock shaft within the containing chamber aforesaid and operatively connected to said valve stem, substantially as set forth.

3. The combination in a flush valve, of an open top casing formed with an upper containing chamber and intermediate piston chamber and lower inlet and outlet chambers, a transverse partition of an approximately V-shape separating said inlet and outlet chambers and having a communicating passage and valve seat, a cap closing the open upper end of the casing and having a central guide bore, a piston in the aforesaid piston chamber formed with a central guide bore, a valve head carried by said piston and controlling the passage between the inlet and outlet chambers aforesaid, a tubular valve stem having vertical movement in the guide bores of the piston and cap aforesaid, and provided with a lateral passage in its wall and opening into the aforesaid piston chamber, means within the valve stem for regulating the size of said lateral passage, the same comprising a valve rod having a tapered lower end and an enlarged screw-threaded upper end engaging a similarly formed portion of the bore of the tubular valve stem aforesaid, an auxiliary valve head carried on said valve stem at a point above the lateral passage aforesaid, a removable partition separating the aforesaid containing and piston chambers and having a central valve seat and passage controlled by said auxiliary valve head, means providing communication between the containing and outlet chambers aforesaid, resilient means for moving the aforesaid valve stem upwardly, and means for imparting positive downward movement to said valve stem, substantially as set forth.

Signed at Chicago, Illinois, this 26th day of January, 1916.
